James Coppock of Jefferson Co. Ky.
Letter Patent

The schedule referred to, in these Letter Patent, and making part of the same, containing a description in the words, of the said James Coppock, himself, of his improvement in the machine for moulding brick, file No.

I now all men by these presents : That I, James Coppock, of the County of Jefferson, State of Kentucky, have invented a useful machine to facilitate the mode of making Brick, and that the following is a full and exact description thereof. This machine consists of a box in which are placed a system of knives affixed to a vertical beam which has a circular motion on its own axis, being moved by horse or other power acting on the beam A. the clay is thrown into the box and thereby these knives prepared and forced down. A polygonal figure B. (which may be of any number of sides and is a regular circular figure) is placed immediately below the box and to which by a system of cogwheels, a.a.a. a rotary motion is given by the power which acts on the inclined beam A. The axis C. around which this figure revolves is fixed an eccentric Kam D encompasses this axis and is also immovable. This Kam is formed by the intersection of two circles, the difference of whose radii is equal to the contemplated thickness of the brick to be moulded. E. & F. are Kam rods which bear upon their ends, h.h. the bottom of the brick mould G. H. and these Kam rods are permanently attached to a yoke (called the Kam yoke) I. O. d. e. f. which by the revolution of the polygonal figure of which the moulds occupy, each a side is caused to revolve around the beam D. now when the yoke shall pass the point G. it will move on the periphery of the circle q.h.j. until it reaches the point j. when by the pressure of the Kam upon the yoke, the Kam rod E. will be pushed out of place a distance equal to the difference of the radius of the circles, and the moulds will be obliged to push out the brick which will be received upon the off bearing plane J. (of which are will speak directly). The Kam rod F. being at the point G. at the same time that the Kam rod E. is at the point j. will be pulled in the same distance that E. is pushed out

and will be ready to receive the clay from the upper box K, as the figure -
 revolves the moulds pass a roller to which prises the clay by the action of a
 lever M, as it passes a roller which touches the polygon in a
 line of which is the projection on a vertical plane. This scraper cuts off all
 superfluous clay which may be attached to the moulds, another roller is passed
 in the revolution of the moulds which serves to conform the figure which is
 given to the brick - now when the moulds reach the point at which it de-
 liveres, the brick is by the principle before described pushed out on this off-
 bearing plane which has a motion on the rollers & equal to the velocity of
 the polygonal figure and which motion is imparted to the rollers by straps
 passing around them and around a circular figure attached to one extremity of and the periphery of which is equal to that of an exterior
 circle of the polygonal figure B. This principle may be applied by the
 mere prision of a Kam represented by the dotted curve M upon a beam
 running the whole length of the moulds, or it may be applied by the use
 of the lever X upon which the Kam prises as before described -
 The accompanying drawings 182 will give a full view of the whole in perspective
 and the drawing 3. will show a vertical section through the centre of the
 vertical beam which rests in the box K. I have contemplated the applica-
 tion of the principle of this machine, to the moulding and delivery of brick
 as well as the casting of any other solid which by the process could be converted
 into a definite form. If the moulds are made of the proper material any
 specific form may be given to malleable metals, and I flatter myself that
 I have invented a machine the application of the principle of which may
 save great labor and procure neatness in the formation of brick tile or any
 metal which by action of heat may be converted into the form of such
 moulds as may be desirable.
